UNITED STATES PATENT OFFICE.

ALFRED H. HUMPHREY, OF KALAMAZOO, MICHIGAN.

GAS-LAMP.

SPECIFICATION forming part of Letters Patent No. 740,018, dated September 29, 1903.

Application filed March 26, 1902. Serial No. 99,989. (No model.)

To all whom it may concern:

Be it known that I, ALFRED H. HUMPHREY, a citizen of the United States, residing at the city of Kalamazoo, in the county of Kalamazoo and State of Michigan, have invented certain new and useful Improvements in Gas-Lamps, of which the following is a specification.

This invention relates to improvements in gas-lamps.

It relates more particularly to an improved globe-holder which is particularly adapted for use in a pilot-light construction, although it is applicable to other forms of gas-lamps.

One object of my invention is to provide an improved globe-holder construction in which the globe can be readily attached and detached from the lamp.

A further object is to provide an improved globe-holder construction for use with burners which are embraced in a globe and used in connection with a pilot-light and the means for actuating the same.

Further objects will definitely appear in the detailed description to follow.

I accomplish the objects of my invention by the devices and means described in the following specification.

My invention is clearly defined, and pointed out in the claims.

A structure embodying the features of my invention is clearly illustrated in the accompanying drawings, forming a part of this specification, in which—

Figure 1 is a detailed side elevation view of a structure embodying the features of my invention, portions being shown in section to show the arrangement of the parts. Fig. 2 is a detailed sectional view of the attaching means for supporting the globe-holder and casing. Fig. 3 is an inverted plan of the globe-holder and its connections to the bottom plate F.

In the drawings similar letters of reference refer to similar parts throughout the several views.

Referring to the lettered parts of the drawings, A represents a gas-pipe, which also serves as a support for the lamp or burner.

A depending pin is secured to the lower end of this pipe, and to this pin is secured a plate F, which is perforated or has openings there-

through to permit the passage of air and the operating-chains a a'', which operate the valves of the lamp. The plate F is provided with a circular flange at the top. The casing F' is adapted to pass over the plate F and is formed at its lower end to embrace the flange thereon. This casing or globe-support is slotted at J J. On one side of plate F is a pin I', adapted to engage a slot J. On the opposite side is a hook-shaped pin I, adapted to engage the opposite slot J. This pin can be turned up, so as to clamp the edge of the casing and hold it securely in position, a spring i being provided to put tension on the same. The top of the casing F' is formed to receive and support the casing of the globe. Within the casing F' are arranged the burners B', which may be of any desired pattern, being here illustrated as the Bunsen type and intended to be used in connection with mantles. The burners are connected by lateral arms or pipes B, as clearly appears in Fig. 1. A valve is provided in the coupling A' at the bottom of the pipe A for controlling the admission of gas to the burners. This valve is provided with a cross-arm C', to which are secured the chains a' for the purpose of actuating the same. Above the main valve 75 is a connection D to the gas-pipe E with the upper part of the coupling A'. This is provided with a valve D'', and beyond this valve is a small vertical tip or pipe E, provided with suitable pilot-burner tip, as E', at the top. 80 To the arm r on the valve D'' is secured a coiled spring S, to the lower end of which is secured the operating-chain a''. But brief mention is made of these parts—that is, the valve feature and operating mechanism and 85 pilot-light construction—as they are fully described in Letters Patent No. 696,640, issued to me the 1st day of April, 1902.

From the foregoing description it is apparent that when it is desired to remove the globe for any purpose, such as replacing mantles or adjusting the burners or valves, the same may be quickly and readily done without disturbing any of the connections for the valves or burners and that the same may 90 be quickly and readily replaced.

I have illustrated and described my structure in detail; but I am aware that it is capable of considerable variation without depart-

ing from my invention. For instance, a great variety of retaining means for the casing will readily suggest themselves to those skilled in the art to which my invention appertains.

5 Having thus described my invention, what I claim as new, and desire to secure by Letters Patent, is—

1. In a burner, the combination of a central support A; a perforated plate F having an upwardly-turned flange at its outer edge carried by said support; a globe-supporting casing F', adapted at its lower end to embrace said flange and having suitable notches therein; pins on the said plate adapted to engage said notches; a spring-clip carried by said plate adapted to engage said casing and lock the same in position; a burner and a pilot-light within said casing; burner and pilot-light valves within said casing; and operating-chains for said valves arranged through the perforations in said plate, all coacting for the purpose specified.

2. In a burner, the combination of a central support A; a plate F having an upwardly-turned flange at its outer edge carried by said support; a globe-supporting casing F', adapted at its lower end to embrace said flange and having suitable notches therein; pins on the said plate adapted to engage said notches; a

spring-clip carried by said plate adapted to 30 engage said casing and lock the same in position, all coacting for the purpose specified.

3. In a burner, the combination of a central support; a perforated plate carried thereby; a globe-supporting casing adapted to embrace said plate at its lower end and having suitable notches therein; pins on said plate adapted to engage said notches; a spring-clip adapted to engage said casing and lock it in position; a burner and a pilot-light within 40 said casing; burner-valves within said casing; and chains for operating said valves arranged through the perforations in said plate, all coacting for the purpose specified.

4. In a burner, the combination of a central support; a plate carried thereby; a globe-supporting casing adapted to embrace said plate at its lower end and having suitable notches therein; pins on said plate adapted to engage said notches; a spring-clip adapted to engage said casing and lock it in position, 45 all coacting for the purpose specified.

In witness whereof I have hereunto set my hand and seal in the presence of two witnesses.

A. H. HUMPHREY. [L. S.]
